UNITED STATES PATENT OFFICE.

CARL F. HAAS, OF SOUTH BEND, INDIANA, ASSIGNOR TO WESTINGHOUSE ELECTRIC AND MANUFACTURING COMPANY, A CORPORATION OF PENNSYLVANIA.

DESIGN FOR A LAMP SUPPORT.

Application filed December 17, 1927. Serial No. 24,519. Term of patent 14 years.

To all whom it may concern:

Be it known that I, CARL F. HAAS, a citizen of the United States, residing at South Bend, in the county of St. Joseph and State of Indiana, have invented a new, original, and ornamental Design for Lamp Supports, of which the following is a specification, reference being had to the accompanying drawing, constituting a part hereof.

The figure is a side elevation of a lamp support showing my new and ornamental design therefor, the dotted line portions being shown for the purpose of disclosing the manner in which the lamp support is used.

I claim:

The ornamental design for a lamp support, substantially as shown.

In testimony whereof, I have hereunto subscribed my name this 9th day of December, 1927.

CARL F. HAAS.
